UNITED STATES PATENT OFFICE.

MORRIS BORRIS, OF BROOKLYN, NEW YORK.

DESIGN FOR A TONE-ARM.

55,449.

Specification for Design.

Patented June 15, 1920.

Application filed April 7, 1920. Serial No. 372,080. Term of patent 14 years.

To all whom it may concern:

Be it known that I, MORRIS BORRIS, a citizen of the United States, and a resident of the city of New York, Coney Island, borough of Brooklyn, in the county of Kings and State of New York, have invented a new, original, and ornamental Design for a Tone-Arm, of which the following is a specification, reference being had to the accompanying drawing, forming part thereof.

Figure 1 is a plan view of a tone arm showing my new design.

Fig. 2 is a side view of the tone arm shown in Fig. 1.

I claim:

The ornamental design for a tone arm as shown.

MORRIS BORRIS.
